UNITED STATES PATENT OFFICE.

IRWIN O. BAUER, OF CINCINNATI, OHIO.

UPHOLSTERY-BINDING.

1,263,734.

Specification of Letters Patent. Patented Apr. 23, 1918.

Application filed December 3, 1917. Serial No. 205,015.

To all whom it may concern:

Be it known that I, IRWIN O. BAUER, a citizen of the United States, and residing at Cincinnati, in the county of Hamilton and 5 State of Ohio, have invented new and useful Improvements in Upholstery-Bindings, of which the following specification is a full disclosure.

My invention relates to a binding or gimp 10 primarily as a vehicle upholstery trimming.

An object of the invention is to provide a vehicle upholstery binding with a flap for concealing and protecting the fastener heads used in applying the binding.

15 Another object of the invention is to provide a binding of plural ply having raised or beaded edges with a hinged tack covering flap between the edges.

Another object of the invention is to form 20 a binding from a single tape of material folded into plural ply, with the laps of the fold secured together by a longitudinal line of stitches, leaving an edge of an outermost double ply lap free.

25 Other features of the invention will be more fully described in a description of the accompanying drawings, wherein:

Figure 1 is a plan view of a portion of the improved upholstery binding, showing a 30 portion of the fastener covering flap thereof of folded back or turned up at one end.

Fig. 2 is an enlarged section of the binding taken on a line 2—2, Fig. 1, and as applied as an upholstery trimming.

35 The binding, as an article of commerce, comprises a body portion 1 having beaded or raised opposite edges 2—2 longitudinally, and a cover flap 3 normallylapping over the body portion intermediate of the beaded 40 edges. The cover flap is adapted to be hingedly turned or folded upward exposing the body portion beneath, when applying the binding, so that the tacks or fasteners may be driven through the body portion leaving 45 the cover flap free, for concealing and covering the heads of the fasteners. The fastener heads are thus protected from the weather, which is of advantage when the binding is used for vehicle upholstery.

50 Common flat-head steel tacks may be used in securing the binding. The heads of the tacks or fasteners are concealed by the cover flap and therefore do not detract from the appearance of the binding, so that a higher 55 quality of finish can be produced. The beaded edges of a binding form a channel

within which the cover flap snugly lies and is confined, preventing it from curling upward when in use. The flap is preferably of double ply adding stiffness to maintain 60 it in a flat condition below the plane of the beaded edges.

The binding in its manufacture is formed of a single tape of material of a required width folded upon itself into plural ply, to 65 comprise the following parts:

The tape along one margin longitudinally is folded upon itself and over a cord 4 at the line of fold to provide a lap 5. This lap 5 is cemented to the intermediate or base 70 portion 6, which it overlies, temporarily holding the lap flat upon the base portion.

The opposite margin of the tape has its material folded upon itself, making a two 75 ply thickness, with the lap 7 of the fold cemented to the tape portion which the lap 80 overlies, and adapted to form the cover flap 3 of the finished product. This double ply portion as a lap is folded upon the base portion 6 and lap 5, and over a cord 8 at the 85 line of fold. The cords 4 and 8 forming raised and rounded beaded edges of the binding, serving as an edge reinforcement giving body and stiffness to the strip, provide a pocket for the cover flap, and ornamentation to the finished product. After the parts have been folded they are permanently secured by a line of stitches 9, adjacent the cord 8 and rear edge of the flap 3, through all of the layers and laps of the 90 folded tape, leaving the forward edge of the flap free to be turned up for tacking and binding.

Having described my invention, I claim:

1. An upholstery binding comprising a 95 strip folded into plural ply, having beaded edges longitudinally, a double ply flap as a layer of the strip intermediate of said edges, and stitches securing said plies along an inner line of one of the beaded edges leaving 100 the flap free to be swung upwardly along the line of stitching.

2. An upholstery binding comprising a strip folded into plural ply having cords longitudinally within the edge folds to provide beaded edges, a flap as a ply of the strip intermediate of said edges and stitches securing said plies along an inner line of one of the beaded edges leaving the flap 105 free to be swung upwardly along the line of 110 stitching.

3. An upholstery binding comprising a

tape of material folded longitudinally into plural ply strips forming a body portion and opposite laps over said body portion, one lap overlying the other, and the parts 5 secured together by a longitudinal row of stitches along a margin of the strip leaving the edge of the upward lap free to provide a hinged cover flap.

4. An upholstery binding comprising a 10 tape of material folded longitudinally into a plural ply strip forming a body portion and opposite laps over said body portion, one lap of double ply overlying the other, said parts secured together by a longitudinal 15 row of stitches along a margin of the strip leaving the edge of the uppermost lap free to provide a hinged cover flap, and cords within the edge folds formed by said lap.
5. An upholstery binding strip formed of

a single tape of material folded upon itself 20 into plural ply, comprising a central portion of the strip width, folds from each side of the central portion as layers overlying each other and said central portion, the uppermost layer folded upon itself to provide 25 a double ply flap, and a line of stitches securing all of the layers to said central portion along a margin thereof and adapting said flap to be swung upwardly from said line of stitches.

30

In witness whereof, I hereunto subscribe my name, as attested by the two subscribing witnesses.

IRWIN O. BAUER.
